UNITED STATES PATENT OFFICE.

OLIVER K. CHANCE, OF OSAKIS, MINNESOTA.

FORCE-PUMP.

SPECIFICATION forming part of Letters Patent No. 340,092, dated April 20, 1886.

Application filed November 12, 1885. Serial No. 182,563. (No model.)

To all whom it may concern:

Be it known that I, OLIVER K. CHANCE, a citizen of the United States, residing at OSAKIS, in the county of Douglas and State of Minnesota, have invented a new and useful Force-Pump, of which the following is a specification.

My invention relates to improvements in double-acting lifting-pumps; and it consists in combining with a pump-casing adapted for two vertically-reciprocating valved pump-buckets certain devices, whereby said buckets can be operated very advantageously, as will be fully understood from the following description, when taken in connection with the annexed drawings, in which—

Figure 1 is a side elevation, partly in section, showing my improved pump arranged in a well. Fig. 2 is a cross-section, enlarged, of the pump-casing, showing a bucket and its lower chain-connections, piston-rods, and cross-head.

In the annexed drawings, A designates a section of a well; A', the platform at the top thereof, and A² the base-stool of the pump-casing, the feet of which are anchored into the well-curbings, as shown in Fig. 1.

B designates the pump-casing, which consists of two vertical cylinders open at the bottom, and provided at their upper ends with valves a a, which open into a dome, b, from which the discharge-pipe b' rises to the top of the well. The pump-casing B is mounted upon and suitably secured to the stool A².

C C designate two tubular pump-buckets, provided with valves c c, which open upward, and also with bails d d, which are connected by a chain, d', that passes under a pulley, D, journaled in the stool A². To each one of the buckets are applied piston-rods e e, connected at their upper ends by a cross-head, e', which heads are connected by chains f f directly to the grooved peripheries of two oscillating pulleys, E E, of equal diameter, and are arranged in the same horizontal and vertical planes, so that the chains f f are always coincident with the vertical axes of the pump-cylinders and buckets therein.

G designates a standard mounted upon the platform A', and affording a fulcrum, g, for a

long hand-lever, H. The lower end of this lever H is pivoted at h to the inner ends of two links, J J, the outer ends of which are pivoted to arms or levers K K, that are fastened to the journals of the oscillating pulleys E E.

It will be seen from the above description that by vibrating the hand-lever H reciprocating motions are imparted to the pump-buckets, and that as one bucket ascends the other bucket descends, thus giving a continuous flow of water through the discharge-pipe.

I am aware that it is old in compound or twin pumps to connect pistons at their lower ends by a chain passed under a pulley; also, that in such pumps working-beams have been connected by chains to the upper ends of the pistons. Such contrivances I broadly disclaim.

What I do claim as novel is—

1. The combination, with the double pump-casing, of the stool A², anchored in the well-curbings and bearing a pulley, the valved buckets in said casing, the chain connecting said buckets and passed under said pulley, the dome at the top of the casing, having a discharge-pipe, the valves opening into the dome, the bucket or piston rods connected by chains to oscillating pulleys, and the compound system of levers, as described, for actuating the buckets.

2. The combination, with the pump-casing, its buckets, the connecting-chain, the piston-rods, and pulley, of the chains f f, connected to the peripheries of oscillating pulleys, the hand-lever, the links J J, pivoted to this lever, and the levers K K, connected to the journals of said oscillating pulleys, all adapted to operate substantially as described.

3. The combination, with a double-acting pump, as described, and its chain connections, of two oscillating pulleys, E E, of equal diameter, and having their sides in the same vertical plane and their axis in the same horizontal plane, the levers K K on the journals of these pulleys, the vibrating hand-lever, and the link-connections of this lever with the said levers K K, substantially as described.

OLIVER K. CHANCE.
